UNITED STATES PATENT OFFICE

160,270

COMBINED FOOTBALL DOWN MARKER
AND INDICATORWilliam F. Musch and Russell S. Katz, Hamilton,
Ohio; said Katz assignor to said Musch

Application August 18, 1948, Serial No. 148,156

Term of patent 14 years

(Cl. D34—5)

To all whom it may concern:

Be it known that we, William F. Musch, a citizen of the United States, residing at Hamilton, in the county of Butler and State of Ohio, and Russell S. Katz, a citizen of the United States, residing at Hamilton, in the county of Butler, State of Ohio, have invented a new, original, and ornamental Design for a Combined Football Down Marker and Indicator, of which the following is a specification, reference being had to the accompanying drawings, forming a part thereof.

We claim:

The ornamental design for a combined football down marker and indicator, substantially as shown.

WILLIAM F. MUSCH.
RUSSELL S. KATZ.
